DESIGN FOR A BEVERAGE CONTAINER

John M. Schilling and Willard G. Schilling,
Lima, Ohio

Application February 12, 1934, Serial No. 50,701

Term of patent 3½ years

To all whom it may concern:

Be it known that we, John M. Schilling and Willard G. Schilling, citizens of the United States and both residing at Lima, in the county of Allen and State of Ohio, have invented a new, original, and ornamental Design for Beverage Containers, of which the following is a specification, reference being had to the accompanying drawing, forming a part thereof.

Fig. 1 of the drawing is a perspective view of our new beverage container design taken from the front end thereof, and

Fig. 2 is a perspective view of our new beverage container design taken from the back end thereof.

We claim:

The ornamental design for a beverage container as shown and described.

In witness whereof, we hereunto subscribe our names this 7 day of Feb., A. D. 1934.

JOHN M. SCHILLING.
WILLARD G. SCHILLING.
